MAXWELL MAYHEW UPSON, OF ENGLEWOOD, NEW JERSEY.

APPARATUS FOR MAKING CONCRETE PILES.

Application filed October 11, 1924. Serial No. 743,166.

The invention which forms the subject of the present application relates to making concrete piles of the type which is wholly or partly molded in situ, and its chief object is to provide simple and effective means by which a circumferentially corrugated shell or mold of sheet metal may be sunk into the ground to the desired depth without the necessity of protecting the outside of the shell during the sinking operation. For this purpose the corrugated shell is fitted on a correspondingly corrugated core, which takes the driving impact or pressure and by its engagement with the corrugations on the inside of the shell draws the shell down into the ground without permitting the shell as a whole to stretch under the pull and thereby flatten out the corrugations. It is thus possible to utilize the well known resistance of circumferential corrugations to high pressures exerted in a radially inward direction, and at the same time use thin metal without the necessity of enclosing the shell in an outer pipe (during sinking) to prevent its being subjected to longitudinal stretching stresses. I am therefore able to eliminate in practically all cases the costly wire reinforcement heretofore used to strengthen pile shells against the pressure of the earth, and at the same time I can make the shell itself of thinner stock. The net result is an important saving of material, in some cases as much as fifty per cent, with the production of a pile which is in no way inferior and which is in some respects superior to piles made by prior methods.

In practice the shell which I employ may be composed of sections arranged end to end and suitably connected or it may be in a single length, according to the length of the pile. The corrugations are preferably helical, in the form of one or more screw-threads, thereby permitting successive sections to be firmly joined by screwing one into the other, the end of one section being slightly belled or expanded to receive the other section, or the end of the latter being slightly reduced to enter the end of the other. This method of joining the sections is particularly advantageous, as it locks the sections and makes the shell in effect a unitary tension member, enabling it to resist the powerful longitudinal stresses exerted by upheaval of the ground, which might otherwise pull the sec-

tions apart and rupture the concrete before the latter has set. Or both methods may be resorted to; or the belled end of one or the reduced end of the other, or both, may be uncorrugated to provide a simple form of joint which is more or less of the bell-and-spigot type. For some purposes the shell is of uniform diameter or roughly cylindrical throughout, or part or all of it may taper downwardly, and the bottom may be closed by a driving point or boot or may be provided with a driving ring. The core or mandrel with which the shell is combined for driving purposes, and which is provided with outer corrugations to engage the inner corrugations of the shell, is preferably non-collapsible and is unscrewed to free it from the corrugations of the shell. This type is especially suitable for a tapered shell, since a few turns suffice to clear the corrugations and leave the core free for withdrawal by hoisting. The core may also be made in longitudinal sections.

Referring now to the accompanying drawings, in which the preferred embodiment of the invention is illustrated:

Fig. 1 is a vertical section showing a tapered shell and core sunk in the ground.

Fig. 2 is a plan view of the driving head of the core shown in Fig. 1, containing the mechanism for rotating the core to unscrew the same.

Fig. 3 is a detail view of the upper portion of Fig. 1, showing the core lifted part way out of the shell after being disengaged by unscrewing.

Fig. 4 is a detail cross section showing one of the fins with which the shell may be provided to prevent rotation as the core is unscrewed.

Fig. 5 is a side view of a jointed shell, partly in section, showing a modified form of corrugation.

Fig. 6 is a vertical section illustrating an untapered core composed of longitudinally separable sections which are screwed together and into successive sections of the shell.

Fig. 7 is a sectional plan view on the line 7—7 of Fig. 6.

Fig. 8 is a detail sectional view of the corrugated core and shell illustrated in Fig. 1, showing the preferred relation between the ribs on the core and the grooves in the shell,

leaving a clearance at the top of the ribs to facilitate unscrewing the core from the shell.

The tapered shell 71 is composed of short lengths or sections corrugated circumferentially in screw-thread fashion. If necessary the upper end of each lower section is "belled" or enlarged enough to permit the lower end of the section next above to be screwed into it, as shown. This gives a 10 taper joint which is very strong and which in some cases can be made sufficiently watertight without the use of fibrous or other packing. On the bottom of the lowermost section is a driving boot 46, screwed into 15 place.

A tubular driving core 72 is employed, having screw-threaded corrugations to screw into the correspondingly corrugated shell. The core is rotatably mounted in the head 20 73, and can be rotated by a worm 74 meshing with a worm gear 75. To prevent rotation of the head 73 it is provided with ears 76 providing grooves adapted to align with similar grooves 77 in the hammer-base 78 25 and embrace the leaders or leader-extensions (not shown) of the pile driver. By reason of the taper a few turns of the core are enough to engage the corrugations of the shell after the two have been assembled, and, 30 similarly, a few turns are enough to free it from the shell-corrugations, after which it can be lifted out, as in Fig. 3, by the cables 79. The hollow core is preferably provided with numerous small openings, as 80, through 35 its wall, and with a suitable nipple 81 for connection with a source of air, water, or other fluid under pressure, which, escaping through the openings, will tend to press the shell outwardly and thereby diminish the 40 friction on the core, making the unscrewing operation easier. In some cases the frictional resistance may be so great as to rotate the shell along with the core, especially in wet or very soft soil. To prevent such a 45 result the shell may be provided with lateral ears or wings, as 82 (see also Fig. 4), riveted or otherwise fastened in place on the shell.

It will be understood that after the core is removed plastic concrete is deposited in the shell, with or without reinforcement, to 50 form the pile.

The shell may be of metal of any suitable thickness, say from 20 to 24 gauge, and may be made in the manner described in my Patent No. 1,491,832, hereinbefore mentioned.

The corrugations may be of the wave type, as in the figures so far referred to, preferably about a quarter or five-sixteenths of an inch deep, and an inch or an inch and 60 a quarter apart from crest to crest. In some cases a form of corrugation such as shown in Fig. 5 will be found advantageous. In this figure the lower face 122 is more nearly horizontal, on both the core 123 and 65 the shell 124, thus diminishing the wedging

effect of the core and correspondingly reducing the possibility of splitting the shell in driving in hard ground.

In the sectional core of simple construction shown in Figs. 6 and 7, the core sections 70 112 have bell-and-spigot joints which may be of the tapered-thread type, as at 113, the pitch of the threads in this joint being the same as the pitch of the corrugations of the shell. The core itself is non-collapsible and 75 is screwed into and out of the shell, section by section. For this purpose each section is provided with inner lugs 114, to be engaged with a suitable wrench or spanner, not shown.

The hollow core 112, shown in Figs. 6 and 7, being open at the bottom, it will be found to be filled with a core of earth when the sinking is completed, which must be removed before the shell can be filled with concrete. 80 This removal can be effected, preferably before the driving core is unscrewed, by blowing the earth out by means of an air-jet (not shown herein), as illustrated in my Patent No. 1,491,832, above referred to.

The driving point used on a hollow core which is open at the lower end, as in Fig. 6 for example, may be in the form of a short tube 111 of relatively thin metal. When "resistance" is encountered, in the form of 90 bedrock or other impenetratable material, as the driving proceeds, the ring will crush down, and by its cushioning effect give warning of the rock in time to prevent shattering or other damage to the costly core. 100 If the surface of the rock encountered is sloping, the ring will crush down on one side first, thus fitting itself to the surface of the rock and sealing the bottom of the shell against rapid inrush of water.

Fig. 8 illustrates a relation between the core-corrugations or ribs and the grooves of the shell which can be employed to advantage with any type of core, tapered or cylindrical, whether made in one piece or 110 in sections. As indicated, the spacing of the corrugations (from crest to crest) is the same in both core and shell, but in the former the corrugations or ribs are slightly narrower so that when the core is driven 115 spaces will be left between the upper surfaces of its corrugations or ribs and the inner surfaces of the corrugations or grooves in the shell, as indicated at 115, for example. The natural compression of the ground in 120 driving tends to lock the shell against the core. In attempting to screw the core out of the shell this friction may be so great as either to disrupt the unscrewing mechanism or to turn the whole shell around in the 125 earth, bringing the shell up with the core. With the clearances 115 provided, the core can be lifted a sufficient distance to relieve the pressure of the shell, thereby permitting the core to be easily unscrewed.

The corrugations are preferably of the screw-thread form, and I also prefer the multiple type, that is, two or more threads running parallel to each other, as this type facilitates assembly of the sections together and on the core. Generally speaking, two threads are enough, but more may sometimes be used without making the "pitch" too steep.

10 It is to be understood that the invention is not limited to the specific constructions herein illustrated and described but can be embodied in other forms without departure from its spirit as defined by the appended 15 claims.

I claim—

1. Means for forming piles or the like including in combination a shell member and a rod like tool member adapted to be embraced by the shell member, said members having their main bodies spaced from each other, one of said members being provided with a spiral groove and the other member having a single screw thread engaging said groove and forming the only contact between the two members, and means for simultaneously forcing the members into soil or the like without rotating either member.

2. Apparatus for forming concrete piles in situ, comprising a sheet-metal shell corrugated circumferentially in screw-thread fashion, a driving core having screw-thread corrugations of the same pitch engaging the corrugations of the shell, the ribs on the core being narrower than the grooves in the shell to provide a clearance permitting the core to be lifted in the shell after driving to relieve the pressure of the latter, and means for rotating the core inside of the shell for removal of the core after the two have been driven.

3. Apparatus for forming concrete piles in situ, comprising a tapered sheet-metal shell corrugated circumferentially in screw-thread fashion, a tapered driving core having screw-thread corrugations of the same pitch engaging the corrugations of the shell, the ribs on the core being narrower than the grooves in the shell to provide a clearance permitting the core to be lifted in the shell after driving to relieve the pressure of the latter, and means for rotating the core inside of the shell to free the core corrugations and permit the core to be lifted out of the shell after driving.

4. Apparatus for forming concrete piles in situ, comprising a sheet-metal shell corrugated circumferentially in screw-thread fashion, a driving core having screw-thread corrugations of the same pitch engaging the corrugations and provided with means for discharging a fluid under pressure upon the inner surface of the shell to facilitate rotation of the core, the ribs on the core being narrower than the grooves in the shell to

provide a clearance permitting the core to be lifted in the shell after driving to relieve the pressure of the latter, and means for rotating the core for removal thereof from the shell.

70

5. Apparatus for forming concrete piles in situ, comprising a sheet-metal shell corrugated circumferentially in screw-thread fashion, a driving core having screw-thread corrugations of the same pitch engaging the corrugations and provided with means for discharging a fluid under pressure upon the inner surface of the shell to facilitate rotation of the core, and means for rotating the core for removal thereof from the shell.

80

6. Apparatus for forming concrete piles in situ, comprising a sheet-metal shell having screw-thread corrugations, a driving core having screw-thread corrugations of the same pitch engaging the corrugations of the shell, a driving head arranged at the top of the core and connected with the core to permit rotation of the latter relative to the head, and means housed in the head for rotating the core.

90

7. Apparatus for forming concrete piles in situ, comprising a sheet-metal shell having screw-thread corrugations, a hollow driving core having screw-thread corrugations of the same pitch engaging the corrugations of the shell and having openings in its wall for the discharge of fluid upon the inner surface of the shell, a driving head arranged at the top of the core, and means for rotating the core inside of the shell for removal of the core after driving.

95

8. Apparatus for forming concrete piles in situ, comprising a tapered sheet-metal shell having screw-thread corrugations, a tapered driving core having screw-thread corrugations of the same pitch engaging the corrugations of the shell, the ribs on the core being narrower than the grooves in the shell to provide a clearance permitting the core to be lifted in the shell after driving to relieve the pressure of the latter, a driving head mounted on top of the core and adapted to permit rotation of the core relative to the head, and means housed in the head for rotating the core to free it from the shell.

105

9. Apparatus for forming concrete piles in situ, comprising a sheet-metal shell having screw-thread corrugations and provided on its outside with means for engaging the soil in which the shell is sunk to resist rotation of the shell, a driving core having screw-thread corrugations fitting the corrugations of the shell and having means for the discharge of fluid under pressure upon the inner surface of the shell to facilitate rotation of the core inside of the shell, and means for rotating the core for removal thereof after driving.

110

10. Apparatus for forming concrete piles

120

- 4
- in situ, comprising a sheet-metal shell having screw-thread corrugations and having means on its outside for engaging the soil in which it is sunk to resist rotation of the shell, a driving core having screw-thread corrugations of the same pitch engaging the corrugations of the shell, and means for rotating the core inside of the shell for removal therefrom.
- 10 11. Apparatus for forming concrete piles in situ, comprising an internally screw-threaded shell, a driving core having external screw threads of the same pitch as the

screw threads in the shell, there being clearance between the said two sets of screw threads when the shell and core are in a predetermined relative axial position, means for driving said core and shell vertically downward, and means for raising said core with respect to said shell to render said clearance effective and subsequently unscrewing said core from said shell.

In testimony whereof I hereto affix my signature.

MAXWELL MAYHEW UPSON.

- in situ, comprising a sheet-metal shell having screw-thread corrugations and having means on its outside for engaging the soil in which it is sunk to resist rotation of the shell, a driving core having screw-thread corrugations of the same pitch engaging the corrugations of the shell, and means for rotating the core inside of the shell for removal therefrom.
- 10 11. Apparatus for forming concrete piles in situ, comprising an internally screw-threaded shell, a driving core having external screw threads of the same pitch as the screw threads in the shell, there being clearance between the said two sets of screw threads when the shell and core are in a predetermined relative axial position, means for driving said core and shell vertically downward, and means for raising said core with respect to said shell to render said clearance effective and subsequently unscrewing said core from said shell.

In testimony whereof I hereto affix my signature.
